[57] CLAIM

The ornamental design for a trash bag holder, substantially as shown and described.

DESCRIPTION

FIG. 1 is a top plan view of a trash bag holder showing our new design;

FIG. 2 is a front elevational view thereof;

FIG. 3 is a side elevational view, the opposite side being a mirror image thereof;

FIG. 4, a bottom plan view thereof;

FIG. 5 is a rear elevational view thereof; and

FIG. 6 is a perspective view thereof shown on a slightly smaller scale and with the cover raised.

In each figure, the wire mesh configuration is understood to repeat continuously across the indicated areas.
